LOCOMOTIVE FEED WATER HEATER

Application filed December 21, 1925, Serial No. 76,828. Renewed April 27, 1931.

This invention relates to a feed water heating apparatus and especially to systems for locomotives in which the water is preheated within the pump receptacle, such systems being described in my co-pending applications Serial Nos. 51,677 and 69,276.

The principal object of the present invention is to provide an improved feed water heating system of this class wherein the water is heated entirely within the pump receptacle itself, approximately to the temperature of the outside exhaust steam supply. With this purpose in view I propose to lead the water in direct contact with the exhaust steam of the pump into a receiving chamber near the top of the pump receptacle, thus condensing the exhaust steam and the water being preheated by the exhaust steam; then to spray the water out of the receiving chamber into a mixing chamber filled with the exhaust steam supply from an outside source (in connection with a locomotive, exhaust steam of the engines and of the auxiliaries) and the water is thus further heated by direct contact with the steam in the mixing chamber to approximately the temperature of the steam. The heated water together with the water resulting from the condensation of the exhaust steam, is collected in the bottom of the pump receptacle which I will call the water chamber from which it is pumped into the boiler.

Another object of the invention is to prevent the water in both the receiving chamber and the water chamber from rising above a predetermined height and for this purpose I propose to discharge the water out of the receiving chamber at a slightly higher rate than out of the water chamber, and to control the water supply to the receiving chamber by the height of the water in the water chamber.

Further objects and advantages of the invention will appear hereinafter. This case includes matter divided out of each of the above mentioned cases.

Reference is to be had to the accompanying drawings, in which

Fig. 1 is a central sectional view of a

feed water heater constructed in accordance with this invention;

Fig. 2 is a horizontal sectional view on the line 2—2 of Fig. 1;

Fig. 3 is a sectional view through the pump receptacle similar to Fig. 1 and showing certain modifications;

Fig. 4 is a view similar to Fig. 1 showing modifications;

Fig. 5 is a sectional view thereof on the line 5—5 of Fig. 4;

Fig. 6 is a vertical central section showing other modifications; and

Fig. 7 is a similar view of another modification.

Referring first to Figs. 1 and 2, the water is fed in through a valve 10, which, under ordinary conditions, is always open and through a pipe 12 into a chamber 11. This chamber is provided with a port having a valve seat in one wall thereof which wall separates it from a second chamber 13 into which the chamber 11 discharges and which discharges into the receiving chamber 127 at the top of the pump receptacle B. A spring loaded stop valve 14 closes this port but it is provided with a plunger 15 in a cylinder 15^a adapted to receive steam behind the plunger to open the valve. The flow of water into the receiving chamber is controlled by the butterfly valve 19 controlled by a float 20 in the pump receptacle, the stem of which passes through a slot 21 in a cover 24 closing the butterfly valve. With the exception of a small amount of water which leaks through this slot, the water is discharged through an upward passage 25, over a perforated plate 76 through which it flows over a baffle plate 72 into the receiving chamber 127 which has a neck 128 and a conical outlet 129. The conical outlet is closed by a spring loaded disc 70, the tension of the spring being adjustable. In the neck of the chamber rotates, on the main shaft 22 passing through the neck of the chamber, an impeller 71, which forces the water downward against the action of the spring so that the water is discharged out of this chamber into the mixing chamber of the pump receptacle in the form of a sheet or cone.

The pump shaft 22 hangs on a ball bearing 23 from the top and has a high pressure turbine wheel 45 and a low pressure turbine wheel 45^a for rotating it. Live steam enters the turbine wheel 45 from the pipe 51 and steam chamber 44 above, through the usual nozzles 44^a (Fig. 2) and exhausts on its lower side into an annular chamber 46 hence, through nozzles 46^b in an angular partition 46^b to the low pressure turbine wheel 45^a, exhausting in a compartment the top of which is formed by partition 46^b and the bottom of which is formed by a partition 47. This partition 47 is provided with a central opening immediately above an opening in the partition 76. The exhaust steam of the turbine passes through said openings being deflected by the deflector 72 and is forced to mingle with the water running through the perforations of plate 76, thereby heating the water and being condensed thereby. From the standpoint of turbine efficiency it is preferable to use two turbine wheels as shown, with turbine blading designed respectively for high and low pressure steam. From the standpoint of simplicity it is preferable to have both the live and the exhaust steam act on a single turbine wheel. Either arrangement comes within the scope of this invention.

The exhaust steam from an outside source is delivered from a pipe 40 to a steam separator 41, from which through a pipe 40^a and a float controlled balanced valve 42 it is delivered to the chamber 46 and the low pressure steam turbine and through a pipe 40^b, and preferably tangentially, into an annular mixing chamber 79 formed by the wall of the pump receptacle B and the bottom, neck and conical outlet of the chamber 27. Into this chamber the cone or sheet of water passes between the conical outlet and the spring loaded disc 70. The chamber 79 is vented to the air. The exhaust steam therefore must pass through this spray of water and heat it. A small chamber 73 leading off the neck 128, is open at the top, and has a small hole at the bottom, therefore a small amount of water will circulate through this chamber 73 being forced through the small hole by the action of the impeller 71. A thermostat 74 is shown in this chamber 73 which closes a butterfly valve 75 in the outlet of the exhaust steam valve 42 at a predetermined temperature of the water passing through this chamber 73.

Live steam is supplied through the valve 50 and steam main 51, to a valve 62 admitting steam to an air ejector 63, and also through a valve 61^a and pipe 61^b to a nozzle 61^c so that the nozzle 61^c is always supplied with live steam as long as the air ejector 63 is in operation. Live steam is also supplied through a valve 61 and valve 43 to the steam chamber 44 containing the other high pressure steam nozzles 44^a. The valve 43 is cast integrally with

the valve 61^a so that if there is no water in pump receptacle B both valves will be closed, but otherwise is, in every respect, the same as in my previous case Serial No. 69,276. The valve 42 has also the same function as in that case.

The exhaust steam being discharged tangentially in the chamber 79 so that it will have a tendency to circulate in this chamber, must pass through the water cone and, no matter how much the back pressure of the exhaust steam may be, it will not be transmitted to the chamber 127 because the chamber 79, and for that matter the water chamber, is not connected to the chamber 127. If there is no water in the chamber 127 the spring loaded disc will close the conical outlet and if there is water the disc is forced downward and then the pressure difference is from chamber 128 to the pump receptacle B. With this construction, therefore, the pressure of the exhaust steam will not hold back the water from the tender because what little might leak through the slot 21 through which the float lever passes, will be immediately condensed. The temperature of the water in the chamber 127, if the pump is run condensing, is limited to the temperature corresponding with the vacuum. Therefore, it is advantageous to have a certain amount of live steam supplied to the high pressure turbine wheel all the time in order to reduce the total steam consumption of the turbines and thereby keep down the temperature of the water in the chamber 127. Therefore, any amount of high pressure steam used in addition to low pressure steam reduces, proportionately, the total steam consumption, as all the steam used by the turbine is condensed into water. Therefore the less weight of steam used the less weight of condensate, and therefore the lower the temperature of the water before it is discharged into the mixing chamber. While this decreases the efficiency of the heater on account of the use of this live steam, on the other hand the efficiency is increased by reducing the amount of steam used by the ejector. In other words, the air ejector does not need to be constantly supplied with steam because a lower vacuum on the exhaust steam turbine will carry the load, which again makes it possible to raise the temperature of the feed water in the chamber 127. The amount of live steam supplied through the nozzle 61^c is determined largely by the lowest capacity at which the pump will have to be run because, at this capacity, the percentage of steam consumption of the water delivered is the highest.

The pump receptacle B is closed by a cover 30 (Fig. 2) containing the high pressure steam chamber 44 and a water chamber 31. Bolted to this cover is a pump volute 32 in which rotates a pump impeller 33 on the vertical shaft 22. To the bottom of the

5 pump receptacle is bolted a pump volute 32^a in which rotates an impeller 33^a on the same shaft 22. Water flows by gravity and by an impeller 29 from the pump receptacle B into the impeller 33^a and is forced thereby through the volute 32^a, and a pipe 31^a into the impeller 33 which forces it through the volute 32 and pipe 34 to the boiler. The impellers are of the single inlet type and the inlet of the impeller 33^a faces the inlet of the impeller 33. The lower impeller 16 chamber has a drain 33^b.

15 The bottom journal of the shaft 22 is shown as in the form of a nut bushing 27^b located in a composition bearing 28. Grease is provided for lubrication in the chamber 27^a formed by the nut bushing and the hub of the cover 32^b which closes the chamber of the volute 32^a.

20 The ball bearing 23 at the top is also lubricated by grease. The bearing is located in a cover 23^a by the removal of which the whole bearing is exposed. The outer face of the bearing rests on a T-ring 23^b the outside 25 diameter of the vertical flange of which is smaller than the outside diameter of the ball bearing and the flange is cut away in two places so that the ball bearing can be pried up and easily removed. The upper face of 30 the inner part of the horizontal flange of the T-ring forms with the lower face of the flange of a bushing 23^c an enclosure of the grease chamber to prevent the grease from running out of the chamber.

35 When the pump is not in operation the two faces will close the chamber tightly and when the pump is in operation the flange of the bushing 23^c prevents, through centrifugal action, the grease from flowing out even 40 if there should be a small upward thrust thereby separating the two faces slightly.

45 A stuffing box of usual construction could be used in combination with means for collecting the water that leaks by the shaft passing through the chamber 31 and returning it to the pump receptacle, but I prefer to provide a wearing ring 80 which fits closely to the distance bushing 81 on the shaft 22 but has some clearance through the 50 casing so that the wearing ring centers around the distance bushing. The water pressure holds it stationary. The water leaking by this wearing ring is collected in a chamber 82 from which it is drained back to the pump receptacle. A screw thread on another distance bushing, with a throw ring 84 thereon, will prevent any great amount of water from escaping downward. If the 55 chamber 82 should ever be filled then this

60 screw thread will put the chamber under a slight pressure discharging the water out of the chamber so much faster, but any water which should leak out downward is caught on top of the turbine wheel which is provided with an annular chamber 85, closed

65 on top but open on the inner side. Any water collecting in this chamber is forced downward by centrifugal force through holes 86 in the turbine, then downward on top of the low pressure turbine wheel, which has a 70 similar chamber to the high pressure turbine wheel and similar discharge holes, so that ultimately any water coming from the water chamber 31 is collected in the low pressure 75 turbine chamber and discharged with the exhaust into the pump receptacle B.

80 The pressure in the chamber of the volute 32 above the impeller 33 is equal to the full discharge pressure of the pump, or approximately double that of the pressure in the water chamber 31. This chamber 32 is closed by a housing, having a chamber 87 closed by a double cover 89 interposed between this housing and the bearing housing 23^a. The shaft passes through the horizontal wall of the chamber and the double cover, the upper part of which forms the bottom of the bearing housing. The space between the two parts of the double cover is open to the atmosphere. I have already explained how 85 the grease is prevented from leaking out of the grease chamber. To prevent the water from leaking by the shaft where it passes through the horizontal wall of the chamber 87, or rather to reduce the leakage to a minimum, I again provide instead of a stuffing box, a wearing ring 88 similar to the wearing ring 80 where the shaft passes through the water chamber 31, and bushing 23^c is 90 provided with a screw thread and a throw ring 91 similarly and for the same purpose as in bushing and throw ring 84. If any water should pass by bushing 23^c it will be 95 discharged to the atmosphere between the lower and upper part of double cover 89. The water in the chamber 87 is drained back to the pump receptacle like the water in 100 the chamber 82.

Operation

110 To start the pump the valve 50 is opened fully. This allows steam to flow through the pipe 51 into the pipe 52 opening the stop valve 14 and into the air ejector 63 and water will flow immediately into the pump 115 receptacle B. Now, the float 49 will rise opening the valves 42 and 43 and live steam and also exhaust steam will flow into the respective turbines. As an excess pressure 120 governor without manual means for opening the valve is used, the valve 61 will be open and will maintain a predetermined excess pressure.

125 As soon as water flows into the pump receptacle B and until the water gives out, live steam is constantly supplied through the nozzle 61^c, but otherwise the regulation of the admittance of the live and exhaust steam may be identical with that in my application Serial No. 69,276.

Fig. 3 shows a modification of Fig. 1 in which the impeller and the conical outlet are replaced by an impeller 71^a which is fastened to the shaft 22 and through the centrifugal force exerted by this impeller the spring loaded disc 70 is forced downward and the water allowed to escape also in cone or sheet form. The rotating deflector in Fig. 1 is replaced by a stationary deflector 72^a, but in every other respect the construction is the same.

Fig. 7 is like Fig. 1 in all respects except that the valve 75 is pressure controlled instead of being controlled by temperature. A plunger 54 forces back a rod 55, against the action of a spring 56 under pressure. The water in the chamber 127 will turn into steam under certain conditions of temperature and vacuum. When this happens there is no pressure below the impeller 71, in which case the spring 56 closes the valve 75 but if a thermostat were used, the thermostat would perform this function.

Figs. 4 and 5 show the invention in a simpler form with other modifications. Many parts of Fig. 4 are not numbered as they are exactly the same as Fig. 1. The water inlet is controlled by a butterfly valve 19 as before, but instead of being direct connected to the float 20, has an arm which is connected by a link 100 to another arm on a shaft on which the float arm is mounted so as to eliminate the slot through which the float arm passes in Fig. 1.

The means for forcing the water down from the chamber 127 is a regular centrifugal impeller 101 discharging the water through guide vanes 102 into a chamber 103 which is provided at the bottom with a spring loaded spray valve 104. This valve, however, is not mounted directly on the shaft 22 but on a bushing 105. The spring 106 acts against the bushing and not against the valve proper so that the valve rests slightly away from its seat to permit drainage, but can be raised by the pressure of the exhaust steam in the mixing chamber so as to prevent the exhaust steam from escaping by the valve when the impeller 101 is not delivering water. The exhaust steam from an outside source 40 is shown as being introduced below the spray, as can be done also in Fig. 1.

The valve 43 is also differently connected with the other parts in that it is made integral with another valve 62 in Fig. 4 allowing steam to flow to the air ejector nozzle through a small hole, thereby reducing the pressure of the steam at the nozzle. This is desirable in order to supply the nozzle with the most efficient steam pressure. The function of the additional valve is to put the air ejector in operation when there is no water in the pump receptacle, which is very essential if the pump is so located that water does not flow to it by gravity all the time. If there is wa-

ter in the pump receptacle then this valve 62 is closed as shown. If there is no water in the pump receptacle, then, of course, the safety valve 43 is closed by the float 49.

The excess pressure governor 60 is also differently connected in that it consists of two compartments 107 and 108 and the steam chest also consists of two separate compartments 107^a and 108^a. Live steam is allowed to flow through the inlet 109 of the excess pressure governor, by-passing the valve through an opening 90 into one compartment 108^a of the steam chest so that always sufficient steam is supplied to the turbine through nozzles 91 to deliver the minimum amount of water. For larger capacities the steam flows through the valve 92 of the excess pressure governor into the other compartment 107^a of the steam chest and into the turbine through additional nozzles 94 and is regulated by the excess pressure governor 60 as before.

Therefore, for the minimum capacity of the pump or for any pre-determined capacity, the steam is delivered to the turbine at full boiler pressure, instead of being throttled by the excess pressure governor, thus increasing the efficiency of the turbine and consequently of the pump. This form also eliminates one turbine and the thermostatic control as the latter is not needed.

Instead of having the steam to the second compartment 107 of the steam chest regulated by the excess pressure governor, this regulation may be done manually. Therefore, instead of controlling the capacity of the pump by the discharge valve, which is always done in connection with an excess pressure governor, the capacity of the pump may be controlled by a steam supply valve consisting of the valve body of the excess pressure governor. This admits steam to one compartment of the steam chest and the steam to the other compartment is regulated by closing or opening the valve.

In Fig. 6 I have shown other modifications coming within the scope of this invention. The arrangement is similar to that shown in Fig. 4, as will be seen by comparison of the numbered parts, but the chamber 103 discharges through one or more parts 95. Each is closed by a spring pressed valve 96 conical on top. The springs are held by spiders 97. These valves open when the pressure in the chamber 83 is enough higher than that over the water to overcome the resistance of the adjustable springs.

These constitute less expensive and lighter arrangements for securing some of the above mentioned results.

It will be seen therefore that, by this invention, as so far described, the water is pre-heated in the pump receptacle by the exhaust from the turbine driving the pump and by the exhaust from an outside source to the

maximum temperature of the outside exhaust steam supply. Also, the pump is driven by a turbine fed in the main by exhaust steam but supplemented by live steam all the time the 5 ejector is working and there is enough water in the pump, and in such proportion and at such time as will give the unit the most efficient heat balance. The water is fed into the receiving chamber and spread 10 out so as to receive the maximum amount of heat from the exhaust steam from the turbines as the water enters the pump receptacle. Furthermore, additional heating is provided for by spraying the water into the 15 lower part of the pump receptacle and subjecting it to the action of exhaust steam from an outside source at that time. The control of the admission of exhaust steam to the turbine is in the form of a thermostat operated 20 in accordance with the temperature of the water as heated by the turbine exhaust. In other words, it is a self contained pump which performs the entire heating operation within itself and can be constructed in a 25 compact form and of light weight.

Certain elements and combinations are shown but not claimed herein because they are claimed in one of my previous copending applications Serial No. 51,677, filed Aug. 21, 30 1925, and Serial No. 69,276, filed Nov. 16, 1925.

Although I have illustrated and described only a few forms of the invention I am aware of the fact that other modifications can be 35 made therein by any person skilled in the art without departing from the scope of the invention as expressed in the claims. Therefore I do not wish to be limited to the details herein disclosed, but what I do claim is:—

1. In a feed water heating system, the combination with a pump receptacle having a receiving chamber into which the water is introduced, a mixing chamber in position for receiving the water from the receiving chamber, means for introducing steam into the mixing chamber, and a water chamber for receiving the water from the mixing chamber, of means in the pump receptacle for pumping the water from the water chamber, and 40 means operated by said pumping means for forcing the water out of the receiving chamber into the mixing chamber.

2. A feed water heating system, comprising a pump receptacle having a water inlet, a receiving chamber to receive the water, a mixing chamber to heat the water, located to receive the water from the receiving chamber, means for introducing exhaust steam into the mixing chamber, a water chamber in 45 position to collect the heated water from the mixing chamber, a shaft in the receptacle, and means operated by the shaft for forcing the water out of the receiving chamber into the mixing chamber.

3. In a feed water heating system, the com-

bination with a receptacle having a water inlet, a receiving chamber to receive the water, a mixing chamber to heat the water, means for introducing steam into the mixing chamber, and a water chamber connected to collect the heated water from the mixing chamber, of a shaft in the receptacle, means operated by the shaft for forcing the water out of the receiving chamber into the mixing chamber, and means also operated by the shaft for forcing the water out of the water chamber. 70

4. In a feed water heating system, the combination with a pump receptacle having a water receiving chamber, a mixing chamber below the receiving chamber, and a water chamber beyond the receiving chamber, of a pump for forcing the water out of said water chamber, means operating in connection with the pump for forcing the water from the receiving chamber into the mixing chamber, and means for commingling the water with steam during its passage from the receiving chamber. 80

5. In a feed water heating system, the combination with a receptacle having a receiving chamber to receive the water, a mixing chamber to heat the water, and a water chamber in position to receive the heated water from the mixing chamber, of a shaft in the receptacle, means operated by the shaft for forcing the water out of the receiving chamber into the mixing chamber, means operated by steam for driving the shaft, a steam supply therefor, and means for condensing exhaust steam by the water while the latter is on its way to the receiving chamber. 90

6. A feed water heating system comprising a receptacle having a water inlet, a receiving chamber to receive the water, a mixing chamber to heat the water, and a water chamber in position to receive the heated water from the mixing chamber, a pump in the receptacle, means operated by the pump to force the water out of the receiving chamber into the mixing chamber, steam operated means for driving the pump, a steam supply therefor, and means for preheating the water by the exhaust steam from said steam operated means before the water is forced into the mixing chamber. 105

7. In a feed water heating system, the combination with a pump receptacle having a water receiving chamber, a mixing chamber beyond the receiving chamber, and a water chamber beyond the receiving chamber and connected therewith, of a pumping means in the water chamber for forcing the water out of said water chamber, means operating in connection with said pumping means for forcing the water from the receiving chamber into the mixing chamber, means for commingling the water with steam during its passage to the receiving chamber, and means for introducing exhaust steam from an outside source into the mixing chamber. 110

8. In a feed water heating system, the combination with a receptacle having a water inlet, a receiving chamber to receive the water, a mixing chamber to heat the water, and a water chamber in position to receive the heated water from the mixing chamber, of a shaft in the receptacle, means operated by the shaft for forcing the water directly out of the receiving chamber into the mixing chamber, and means for introducing steam into the mixing chamber to heat the water.

9. In a feed water heating system, the combination with a receptacle having a water inlet, a receiving chamber to receive the water, a mixing chamber to heat the water located to receive the water from the receiving chamber, and a water chamber in position to receive the heated water from the mixing chamber, of a shaft in the receptacle, means operated by the shaft to force the water out of the receiving chamber into the mixing chamber, means for driving the shaft by steam, a steam supply therefor, means for preheating the water by the exhaust steam before the water is forced into the mixing chamber, and means for introducing an outside steam supply into the mixing chamber to further heat the water.

10. In a feed water heating system, the combination with a receptacle having a receiving chamber for the water, a mixing chamber, and a water chamber to collect the water, the three chambers being located in vertical alignment to receive the water from each other in succession, of a pump in the receptacle, a pump shaft, means operated by the shaft to force the water out of the receiving chamber into the mixing chamber, steam operated means for driving the pump, a steam supply therefor, means for preheating the water by the exhaust steam before the water is forced into the mixing chamber, means for introducing an outside steam supply into the mixing chamber to further heat the water, and means for limiting the temperature of the water in the receiving chamber.

11. In a feed water heating system, the combination with a receptacle, having a receiving chamber to receive the water, a mixing chamber to heat the water, and a water chamber in position to collect the heated water from the mixing chamber, of a shaft in the receptacle, means operated by the shaft for forcing the water out of the receiving chamber into the mixing chamber, a turbine for driving the shaft, a steam supply for the turbine, means for preheating the water by the exhaust steam of the turbine before the water is forced into the mixing chamber, and means also operated by the shaft to force the water out of the water chamber.

12. In a feed water heating system, the combination with a receptacle having a water inlet, a receiving chamber to receive the

water, a mixing chamber to heat the water, and a water chamber to collect the heated water the three chambers being located in vertical alignment to receive the water one from another, a shaft in the receptacle, means operated by the shaft for forcing the water out of the receiving chamber into the mixing chamber, means for introducing steam into the mixing chamber to heat the water, and means also operated by the shaft for forcing the water out of the water chamber.

13. In a feed water heating system, the combination with a receptacle having a water inlet, a receiving chamber to receive the water, a mixing chamber to heat the water, and a water chamber to collect the heated water the three chambers being located in vertical alignment to receive the water one from another from the mixing chamber, of a shaft in the receptacle, steam operated means for driving the shaft, a steam supply therefor, means for preheating the water by the exhaust steam from said means before the water enters the mixing chamber, means for introducing an outside steam supply into the mixing chamber for further heating the water, and means operated by the shaft for forcing the water out of the water chamber.

14. In a feed water heating system, the combination with a receptacle having a receiving chamber to receive the water, a mixing chamber to heat the water, and a water chamber to collect the heated water, the three chambers being located in vertical alignment to receive the water from each other in succession, of a pump in the receptacle, means for forcing the water out of the receiving chamber into the mixing chamber, a turbine for driving the pump, a steam supply for the turbine, means for preheating the water by the exhaust steam of the turbine before the water is forced into the mixing chamber, means for introducing an outside steam supply into the mixing chamber to further heat the water, and means for automatically shutting off the steam supply to the turbine whenever the water in the water chamber falls below a predetermined height.

15. In a feed water heating system, the combination with a pump receptacle, a rotary pump shaft therein and means on the shaft for operating it, of means for introducing water into the receptacle above the water level, means for introducing steam, a deflecting plate in position for spreading the steam and water and mixing them, a partition below the deflecting plate having a passage through it, and means below said passage for causing the water to be heated before it falls down into the water below.

16. In a feed water heater, the combination with a pump receptacle, means for feeding water into the receptacle near the top, means for discharging the water therefrom, said latter means comprising a steam turbine, and

means within the receptacle for retaining a current of the incoming water adjacent to the exhaust of the turbine for preheating the water within the pump receptacle by exhaust 5 from the turbine.

17. In a feed water heater, the combination with a pump receptacle, means for feeding water into the receptacle, means for discharging the water therefrom, said latter means 10 comprising a steam turbine, and means within the receptacle for causing the in-coming water to flow past the exhaust of the turbine for preheating the water within the pump receptacle, partly by exhaust from the turbine, to the approximate temperature of an outside exhaust steam supply. 15

18. In a pump for a feed water heating system, the combination with the pump receptacle, of a pump shaft, a steam turbine in 20 the receptacle on the shaft, and means for introducing water into the receptacle directly in the path of the exhaust steam from the turbine so that it will be heated within said receptacle by the steam discharged from the 25 turbine.

19. In a pump for a feed water heating system, the combination with the pump receptacle, of a perforated partition across it having an opening for admitting steam below 30 it from above, a pump shaft, a steam turbine in the receptacle above the partition, and means for introducing water into the receptacle above the partition so that it will drip through the perforations and be heated within 35 said receptacle by the steam discharged from the turbine.

20. In a feed water heating system, the combination with a pump receptacle and means for introducing water into it, and means for 40 introducing steam to heat the water in the receptacle, of a pump shaft in the receptacle, a steam turbine on the shaft for operating it, a steam supply pipe, an ejector connected with the receptacle and with the steam supply 45 for reducing the pressure on the exhaust side of said turbine, a valve for controlling the supply of steam to said turbine, means for introducing steam into the turbine independent of said valve, and means connected 50 whereby the turbine will receive an additional supply of steam under the control of said valve to operate under increased load.

21. In a feed water heater, the combination with the pump receptacle and a steam operated impeller for forcing the water out of the casing, of a perforated partition across the receptacle above the water level, means for introducing the water into the receptacle above the partition, means for leading the steam down through said partition so that the steam will be condensed by contact with the water draining through the perforations and heat the water, and means for spraying 60 the heated water into the lower part of the receptacle. 65

22. In a feed water heater, the combination with the pump receptacle and a steam operated impeller for forcing the water out of the receptacle, of a perforated partition across the receptacle, means for leading the steam down through said partition so that the steam will be condensed by contact with the water draining through the perforations and the water will be heated by the steam, an air 70 ejector connected to the pump receptacle below the partition, means on the impeller shaft for forcing the heated water downwardly, and adjustable means for confining the water outlet into the receptacle to force it to form a conical stream in contact with exhaust steam to further heat the water. 75

23. In a feed water heating system, the combination with a pump receptacle, a pump shaft therein, a pump on said shaft, said receptacle having a water space in the bottom, and means for introducing water into the receptacle near the top, of a passage in the receptacle surrounding the shaft for conducting the water down into the bottom of the receptacle, a plate yieldingly held up 80 near the bottom of said passage to provide a thin outlet through which the water is forced out in the form of a thin sheet, said receptacle having a chamber above said sheet bounded by it at the bottom, and means for introducing steam into said chamber to heat the water as it issues from the passage. 85

24. In a feed water heating system, the combination with a pump receptacle, a pump shaft therein and means on the shaft for 100 operating it, of a perforated partition across the receptacle, means for introducing water into the receptacle above the partition so that it will drip down through it, means for introducing steam below the partition, whereby 105 the water will be heated, a partition below the perforated partition having a passage through it, means below said passage for causing the water to be forced outwardly to form a thin sheet of water, leaving a space above said sheet of water, and means for introducing steam into said space, whereby the water in said sheet is heated before it falls down into the water space below. 110

25. In a feed water heating system, the combination with a pump receptacle, a pump shaft therein, and a turbine on the shaft for operating it, of a perforated partition across the receptacle having an opening through it for receiving the exhaust steam from the turbine and conducting it to a point below the partition, means for introducing water into the receptacle above the partition so that it will drip down through the steam below and the water will be heated, a partition below the perforated partition having a central passage through it, an impeller on the shaft in said central passage for forcing the water down through the passage under pressure, means below said passage for causing the water to 115 120 125 130

be forced outwardly to form a thin sheet of water, leaving a space above said sheet of water, and means for introducing exhaust steam into said space, whereby the water in said sheet is heated before it falls down into the water space below.

26. In a feed water heating system, the combination with a pump receptacle, a pump shaft therein, means for rotating the shaft, and means for introducing water into the receptacle, of a passage in the receptacle surrounding the shaft for conducting the water down into the bottom of the receptacle, an impeller on the shaft in said passage for forcing the water downwardly through said passage, a plate on the shaft yieldingly held up near the bottom of said passage to provide a thin slanting circular outlet surrounding said plate through which the water is forced out under the pressure from said impeller in the form of a thin conical sheet, and means for introducing steam into said receptacle to heat the water as it issues from the passage.

27. In a feed water heating system, the combination of a receptacle for the water having a space or chamber in its upper part, means for introducing water, means for heating the water in the receptacle, a turbine in the receptacle, a shaft in the receptacle and its chambers to which said turbine is fixed, means for introducing exhaust steam into said turbine to operate it, a steam separator located in the path of the exhaust steam to said turbine, means for draining the separator into said receptacle, and an automatic valve for controlling the admission of exhaust steam into the turbine, with a thermostatic means for controlling the admission of exhaust steam into the turbine, and means for causing the water to circulate around said thermostatic means.

28. In a feed water heating system, the combination with a receptacle for the water, means for heating the water in the receptacle, said receptacle having an air chamber above the water and a partition across it to provide a chamber at the top, means for introducing water above the partition, and a shaft extending through the receptacle and chambers, of a turbine fixed to said shaft in the chamber above the partition, means for directing exhaust steam into said turbine for operating it, means for supplying live steam to the turbine for operating it, a float device in the receptacle, two valves connected with the float device, one for controlling the admission of exhaust steam to the turbine and the other for control assisting the admission of live steam to the turbine so arranged that they will close when the water in the receptacle gets below a certain level.

29. In a feed water heating system, the combination, with a receptacle for the water, means for heating the water in the receptacle, said receptacle having an air chamber above

the water and a partition across it to provide a chamber at the top, means for introducing water above the partition, and a shaft extending through the receptacle and chambers, of a turbine fixed to said shaft in the chamber above the partition, means for directing exhaust steam into said turbine for operating it, means for supplying live steam to the turbine for operating it, means connected with the live steam supply for ejecting the air from the air chamber in the receptacle, a valve for controlling said means, a valve for controlling the admission of a small supply of live steam constantly to the turbine whenever the ejector is in operation.

30. The combination with a pump for a feed water heating system comprising a receptacle for the water and means for heating the water in the receptacle, a shaft in the receptacle, a turbine on the shaft in the receptacle for operating the shaft, and means on the shaft for discharging the water when the shaft rotates, of an exhaust and live steam supply arrangement for the turbine, an ejector connected with the live steam supply, a valve for controlling the admission of steam to the ejector, said turbine exhausting into the air space in the receptacle, a connection from the air space in the receptacle to the ejector, whereby when the ejector is supplied with steam it will exhaust air from said space and reduce the pressure on the exhaust side of the turbine; a valve for supplying live steam to the turbine, means whereby said valve is normally closed, and means whereby when the load on the turbine is too great for the exhaust steam supply, the valve will open to admit live steam to the ejector and to the turbine and whereby when the work of the live steam is no longer required its main supply will be shut off automatically and thereafter, if the power is still too great, the ejector will be shut off automatically.

31. In a feed water heating system, the combination with a pump receptacle and means for introducing water into it and steam to heat the water in the receptacle, of a pump shaft in the receptacle, a turbine in the receptacle on the shaft for operating it, a main steam supply for the turbine, a valve for shutting off the main supply of steam to the turbine, an ejector connected with the top of the receptacle and with the steam supply for reducing the pressure on the exhaust side of said turbine, a valve for cutting off the supply of steam to said ejector, a governor for operating said valve, and means connected to receive its supply of steam under the control of said valve for introducing steam into the turbine to operate it even when the main steam supply is cut off from said turbine and as long as the ejector is in operation.

32. In a feed water heating system, the combination with a pump receptacle and

means for introducing water into it, and means for introducing steam to heat the water in the receptacle, of a pump shaft in the receptacle, a turbine on the shaft for operating it, a main steam supply for the turbine, an ejector connected with the receptacle and with the steam supply for reducing the pressure on the exhaust side of said turbine, a valve for cutting off the supply of steam to said ejector, a pipe, means for introducing steam through said pipe into the turbine to operate it constantly even when the main steam supply is cut off from said turbine, and means for simultaneously cutting off the steam from the pipe and from the ejector.

33. In a feed water heating system, the combination of a pump receptacle for the water and means for heating the water in the receptacle, a turbine in said pump receptacle for operating it, means for conducting live steam to the turbine, means for conducting exhaust to the turbine, automatic valves for closing said steam conducting means, a thermostat in the pump receptacle, and means for connecting the thermostat with the valve for controlling the exhaust steam supply whereby the exhaust steam conductor will be closed when the water gets too hot in the pump receptacle.

34. In a feed water heater, the combination with a pump receptacle for the water and means for heating the water in the receptacle, a turbine therein for operating the pump, and means for feeding steam to the turbine comprising a main supply pipe, of two steam chambers adapted to receive steam from said pipe, means whereby the pipe is constantly open to one of said steam chambers, a valve for controlling the admission of steam to the other steam chamber, and means connected with each steam chamber for introducing steam into the turbine, whereby the turbine will be operated at full steam pressure and will be supplied with an increased quantity of steam for operating it when the valve is opened.

35. The combination with a pump receptacle, of a turbine therein for operating the pump, and means for introducing steam into the turbine, of an ejector, means for connecting the ejector with the pump receptacle for creating a vacuum therein, a steam supply pipe, a valve for closing it, a valve fixed with respect to said valve for controlling the supply of steam to the ejector, means connected with said valves for closing the first valve when the water gets low in the receptacle, the valves being arranged to open the supply to the ejector when the water begins to drop, and means for heating the water.

36. The combination with a pump receptacle, of a shaft therein having means for forcing the water from the receptacle, a turbine on said shaft for rotating it, a perforated partition extending across the recep-

tacle, means for introducing water into the receptacle beyond said partition, said partition having a passage through which exhaust steam from the turbine passes to heat the water, a partition beyond the perforated partition having a passage for discharging the water heated by the exhaust steam, a plate on the shaft, and a casing surrounding the shaft and slightly separated from the plate at the edge for discharging the water outwardly in a conical stream on the water in the receptacle below.

37. The combination with a pump receptacle, of a shaft extending through it and having means for discharging the water from the receptacle, a turbine on said shaft for rotating it, a perforated partition extending across the receptacle, means for introducing water into the receptacle above said partition, said partition having a central passage through which the exhaust steam from the turbine passes down around the shaft into contact with the water passing through the perforations in the partition, a solid partition below the perforated partition having a central passage around the shaft for discharging the water heated by the exhaust steam, an impeller on the shaft in said passage for forcing the water down, a plate on the shaft, a casing surrounding the shaft and separated from the plate at the edge for the discharge of water outwardly in a conical stream on the water in the receptacle below and yielding means for holding the plate up in position to keep the passage for the escape of water small.

38. In a feed water heating system, the combination with a pump receptacle, of a plurality of water forcing devices in the receptacle connected with the same source of power, one of said devices being adapted to force the water out of the receptacle and the other to direct the water from above into the bottom of the receptacle, means for heating the water, a rotary shaft on which both of said devices are mounted and a turbine on the shaft for rotating it.

39. In a feed water heating system, the combination with a pump receptacle, of a plurality of water forcing devices in said receptacle connected with the same source of power so that the amount of water delivered by each is substantially equal, one of said devices being adapted to force the water out of the receptacle and the other to direct the water into the bottom of the receptacle, means in the receptacle for connecting the two devices positively together, a turbine in the receptacle for operating said connecting means, means for heating the incoming water, and means for directing it in a thin sheet on the surface of the water below.

40. A feed water heating system, comprising a pump receptacle having a water inlet, a receiving chamber to receive the water, a

mixing chamber to heat the water, located in position to receive the water from the receiving chamber, means for introducing exhaust steam into the mixing chamber, a water chamber to collect the heated water from the mixing chamber, a shaft in the receptacle, a turbine on the shaft, a steam supply for the turbine, means operated by the shaft for forcing the water out of the receiving chamber into the mixing chamber and means for automatically shutting off the steam supply to the turbine whenever the water in the water chamber falls below a predetermined height.

41. In a feed water heating system, the combination with a receptacle having a receiving chamber to receive the water, a mixing chamber to heat the water, an exhaust steam supply and a water chamber in position to receive the heated water from the mixing chamber, of a shaft in the receptacle, a turbine on the shaft, a steam supply for the turbine, means operated by the shaft for forcing the water out of the water chamber and means for automatically shutting off the steam supply to the turbine whenever the water in the water chamber falls below a predetermined height.

42. In a feed water heater, the combination with a pump receptacle having a water chamber, means for feeding water into the receptacle, means for discharging the water therefrom, said latter means comprising a steam turbine in the receptacle above the water chamber, and an impeller submerged in the water and operatively connected with the turbine, a steam supply for the turbine, means within the receptacle for heating the water and means for automatically shutting off the steam supply to the turbine whenever the water in the water chamber falls below a predetermined height.

43. In a feed water system, the combination with a receptacle for the water and means for heating the water in the receptacle, said receptacle having an air chamber above the water, a shaft in the receptacle, a turbine fixed to said shaft in the receptacle, means for constantly supplying a small quantity of steam to the turbine for operating it as long as the water in the receptacle is not below a predetermined height and means for introducing a greater quantity of steam into the turbine when needed.

55. In testimony whereof I have hereunto affixed my signature.

FRANS H. C. COPPUS.
